UNITED STATES PATENT OFFICE.

JAMES E. FITZGERALD, OF YOUNGSTOWN, OHIO, ASSIGNOR TO THE NILES STEEL PRODUCTS COMPANY, OF NILES, OHIO, A CORPORATION OF OHIO.

DOUBLE SHIPPING CONTAINER.

Application filed December 24, 1926. Serial No. 156,804.

REISSUED

This invention relates to a double container adapted particularly for the shipment of ingredients for certain kinds of paint, such as aluminum and bronze paint, this article having two compartments or container bodies, one for the liquid and the other for the powder.

The object of the present invention is to provide a double container of this kind including two container bodies, one adapted to be fitted inside the other and both adapted to be closed and sealed in one closing operation and by the same closing member.

A further object is to provide a construction wherein not only are both containers closed in one closing operation but wherein each has a gasket seal, the gasket sealing for both container bodies being preferably accomplished with the use of a single gasket.

20 In the accompanying sheet of drawings, Fig. 1 is a side elevation of my improved double container with both container bodies in closed and sealed condition, parts being broken away; Fig. 2 is an enlarged fragmentary sectional view with the parts in the relative positions which they occupy prior to the closing operation; Fig. 3 is a similar view after the closing operation; and Fig. 4 is a view similar to Fig. 3 showing a slight modification.

25 My improved double container comprises two container bodies 10 and 11, the former being deeper and of slightly greater diameter than the latter so that the smaller container 11 can be slipped down into the open top of the larger container 10. In the use of this double container for shipment of paint ingredients, the liquid is placed in the larger container and the aluminum, bronze or other powder in the container body 11.

30 It will be observed that the larger or outer container 10 is provided at the top with a roller bead 12 and that the inner container 11 has a straight body portion of such diameter that it will just fit and slide down inside of the bead 12. Furthermore, the inner container body 11 is provided at the top with an outwardly extending flange 13 which overlies the bead 12, and this container body has a cover 14 with a depressed part which fits tightly into the top of the container body 11, the cover having an outwardly extending flange 15 which overlies the flange 13 and preferably extends outwardly somewhat further than the flange 13.

In fact, in the preferred embodiment, the outer periphery of the flange 13 is near the circular center line of the bead 12, or it may project slightly beyond the same, while the flange 15 projects outwardly beyond the flange 13 as above stated.

35 In the preferred embodiment of the invention, a single gasket 16 is employed to seal both containers, which gasket is placed between the bead 12 and the flange 13 on the body of the container 11. As far as the broad features of my invention are concerned, it is immaterial whether one gasket or two gaskets are utilized, one between the bead of the outer container and the flange 70 of the inner container, and the other between the flange of the inner container and the flange of the cover. However, when a single gasket is employed, as illustrated in Figs. 2 and 3, it is important that the flange 75 15 of the cover project outwardly further than the flange 13 of the inner container, as will appear presently.

40 For the purpose of closing both container bodies, in one closing operation, a sealing ring 18 is employed, this being a continuous ring having separable ends, which can be formed by overlapping the ends and spot welding or otherwise fastening them together, and being provided also with a downwardly extending flange 17 which fits around the bead 12, and having a horizontal inwardly extending portion which overlies the flange 15 of the cover 14.

45 The downwardly extending flange 17 of 90 the sealing ring is preferably continuous, and in the closing operation a closing tool is employed which first presses the parts down onto the bead 12, compressing the gasket 16, and then crimps spaced portions 95 17^a of the flange 17 inwardly under the bead, leaving between the crimped portions 17^a uncrimped portions 17^b.

50 This type of sealing ring and the described method of closing is more fully set forth in a pending application filed by me August 19, 1926, Serial No. 130,215, wherein the sealing ring is employed for the closure of a single container. It may be here stated, however, that in the closing operation the 100 crimped portions 17^a are bent inwardly tightly against the under side of the bead and generally in contact with the body of the container beneath the bead, these portions being crimped inwardly at substan- 110

tially right angles; and in this crimping operation, the intervening uncrimped portions 17^b are slightly drawn inwardly and where they merge with the crimped portions they are curved inwardly, forming the equivalent of curved arches joining the crimped portions and adding considerably to the strength of the top portion of the closed container.

- 10 With the preferred embodiment of my invention wherein a single gasket is employed, during this closing operation the gasket is not only highly compressed between the bead 12 and the flange 13 but inasmuch as 15 the flange 15 extends outwardly beyond the flange 13, the gasket, by its expansion around or outside of the flange 13, and generally also around or outside of the flange 15, effectively seals the inner container as well, so 20 that leakage of powder from the inner container as well as leakage of liquid from the outer container is effectively prevented by the single gasket 16.

The single gasket, with the sealing ring 25 and with the flanges proportioned substantially as herein described and illustrated, effectively seals both containers as above explained. It is obviously cheaper than a construction employing two gaskets and more 30 economical from the assembling aspect, but, as already stated, I regard it within the scope of my invention to utilize two gaskets, in which event the horizontal flanges on the inner container and cover respectively may 35 extend outwardly co-extensively. The construction when employing two separate gaskets is illustrated in Fig. 4, wherein the flanges on the inner container and cover are designated respectively 13^a and 13^b, and the 40 two gaskets, one between the bead and the flange 13^a and the other between the latter and the flange 15^a are designated respectively 16^a and 16^b. With the two gaskets, the sealing of both container bodies is ac- 45 complished at the same time and by the use of one sealing ring, as in the first described construction.

When it is desired to use the paint ingredients contained in the two container bodies, 50 it is only necessary to separate the separable ends of the sealing ring and then strip the sealing ring off the top of the double container. The inner container can then be lifted out to give access to the liquid in the 55 outer container, and the cover can be lifted from the inner container to give access to the powder therein. It will be understood, of course, that while the container bodies are described as being adapted preferably for 60 receiving respectively the liquid and powder for making aluminum or bronze paint, it is obvious that they may be employed for the shipment of other materials.

I do not desire to be confined to a sealing

ring as an element separate from and inde- 65 pendent of the cover though that arrangement is preferred, for in some instances, the outer sealing flange may be made an integral part of the flange 15 of the cover. In that event, to remove the cover the inwardly 70 crimped portions will be pried outwardly with a suitable tool. Therefore, I do not desire to be confined to the precise details shown and described but aim in my claims to cover all modifications which do not involve a departure from the spirit and scope 75 of my invention.

Having thus described my invention, what I claim is:

1. In a double shipping container, an 80 outer container body having at the top an outwardly projecting shoulder, a gasket overlying said shoulder, an inner container body having at the top a flange overlying the inner portion of the gasket, a cover for 85 the inner container body having a marginal portion extending outwardly over said flange and beyond the same, and a sealing ring having an inwardly extending portion overlapping the marginal portion of the cover 90 and having a flange extending downwardly around said shoulder and adapted to be turned inwardly beneath the same.

2. In a double shipping container, an 95 outer container body having at the top an outwardly projecting bead, an inner container body fitted into the open top of the first named container body and having a flange projecting over said bead for a limited distance radially, a gasket between said 100 bead and the flange and projecting outwardly beyond the latter, a cover having a depressed portion fitted into the top of the inner container body and having a flange overlying the flange of the inner container 105 body, and extending outwardly beyond the same and a sealing ring having an inwardly extending flange overlapping the flange of the cover and having a downwardly extending flange surrounding said bead of the 110 outer container body and adapted to be turned inwardly beneath the same.

3. In a double shipping container, an outer container having at the top an outwardly projecting shoulder, a gasket overlying said shoulder, an inner container having at the top a flange overlying the inner portion of the gasket, a cover for the inner container having a marginal portion extending outwardly over said flange and beyond the same, and means for clamping down said flange and marginal portion to compress said gasket, said means comprising a ring against which the outer periphery of said gasket bears.

In testimony whereof, I hereunto affix my signature.

JAMES E. FITZGERALD.
